UNITED STATES PATENT OFFICE

JULES LOUIS BRETON, OF BELLEVUE, FRANCE

MACHINE FOR WASHING, DRYING, AND STERILIZING DISHES

Application filed January 18, 1926, Serial No. 81,636, and in France January 21, 1925.

The present invention concerns improvements in machines for washing, drying and sterilizing dishes. It aims, more particularly, to simplify and improve the construction and operation of machines in this class of the so-called "continuous" type of design.

One of the objects of the invention is to provide an economical arrangement of heaters and flues for accelerating the drying of the dishes.

Another object is to provide a hot water heater so arranged that the waste heat therefrom is used in the drying operation.

Still another object is to arrange the washing sprays so that they not only clean the dishes but at the same time impel them to move through the machine on suitably arranged carriages or conveyors at any chosen regulatable speed.

Other objects will appear in the course of the detailed description of preferred embodiments of the invention which follows, reference being made to the accompanying drawings in which:

Fig. 1 is a front view, partially in section of a complete machine of the straight-line type.

Fig. 2 is another front view of the same machine showing details of the outside casing.

Fig. 3 is a transverse section through the machine shown in Fig. 1, taken through one of the wash-water reservoirs.

Fig. 4 is another transverse section through the same machine and taken through the hot water heater.

Fig. 5 is an end view of the chain drive showing particularly the disposition of the gutters, and of the guards for protecting the chains.

Fig. 6 is a section through another embodiment of the machine, which utilizes a revolving table.

Fig. 7 is a top view of the machine shown in Fig. 6 with the top removed.

Fig. 8 is a view of the machine illustrated in Fig. 6 showing the outside casing in position.

Fig. 9 is a partial section of the same ma-

chine, the section being taken through the screens leading to the pumps.

In each of the several views similar numerals indicate similar parts.

Referring now to the various figures of the drawing, 1 is a motor directly connected to centrifugal pump 2, and to a worm-and-wheel drive 3 which actuates chain 4 to rotate sprocket-wheel 5 mounted on shaft 6. Shaft 6 is fitted with a pair of sprockets 7 carrying chains 8 which pass over sprockets 9. A series of transverse bars or links 10 connect the two chains 8. A trackway 11 guides the movement of baskets 12 mounted on wheels 13, through the machine. The baskets 12 are provided with brackets 14 carrying pivoted fingers 15 which engage with cross-bars or links 10 connected to the drive chains 8. The interengagement of fingers 15 and links 10 causes the movement of the baskets 12 into the machine and the continued forward movement of each basket is effected by the dish-baskets 12 mounted immediately behind it, which are in engagement with the drive-chains 8. Chains 8 are protected from water and refuse falling from the baskets 12 by the sheet metal plates 16 which are arranged to leave a space 17 for the passage of fingers 15. Gutters 18 are placed beneath space 17 to intercept anything passing therethrough. When the baskets reach the opposite end of the trackway 11 they may be removed through doors 19; but if they are not removed, they actuate plunger 21 to open switch 22 leading to the motor. The machine then comes to a stop. It is to be understood of course that trackway 11 may be prolonged beyond the casing of the machine, in which case the dishes may be removed from the track after they emerge from the casing.

Dish baskets 12 are moved along the trackway 11 and enter a first washing compartment 23 where suitably arranged sprayers 24, 24¹ spray water fed to them by the pump 2 from wash water reservoir 25. The refuse from the dishes falls upon the inclined funnel-shaped screens 26 which empty into refuse baskets 27. The baskets 12 proceed now into compartment 28 where the dishes are again rinsed by sprayers 29, 29¹ fed by pump 100

2 from wash water reservoir 30. Screens 31 are provided to catch refuse falling from the dishes toward reservoir 30. The dish baskets now are moved past sprayers 32, 32¹ which are supplied with clean, hot water coming directly from the coil (see Fig. 1) forming part of the hot water heater 33. The continued movement of the dishes brings them over hot water heater 33 the waste heat from which rises through flue 34 and effects their drying and sterilization. Water heater 34 is heated by a convenient form of gas heater, as shown in Fig. 1.

In order to provide for proper circulation 15 of hot air over the dishes, flue 34^a and chimney 35 are provided immediately over washing compartments 23 and 28. The vigorous movement of air from flue 34 to flue 34^a via the drying compartment, which communicates 20 with and which connects both of these flues, acts to dry the dishes and to sweep the vapors in the washing compartments up into chimney 35. Flue 34^a is provided with a central wall 36, and it is also provided with 25 baffles 37 designed to deflect the wash waters from the sprayers back into their respective reservoirs.

The course of the wash water through the machine is from sprayers 32, 32¹ to reservoir 30, through screen 38, thence through the pump to sprayers 29, 29¹ and back to reservoir 30. Reservoir 30 overflows at 39^a into reservoir 25 from which the wash water is drawn through screen 38¹ into the pump, whence it is elevated to sprayers 24¹ and 24 which deliver the water back to reservoir 25. A valve 40 may be adjusted to discharge foul water from reservoir 25 at any desired rate.

It is necessary that the wash waters projected from sprayers 24, 24¹ for effecting the first rinsing be not above 60° in temperature in order to avoid coagulating the albuminous substances adhering to the dishes. Means must therefore be provided for preventing an excessively rapid transfer of heat from hot water reservoir 30 to the cooler water in reservoir 25. This is accomplished by interposing a heat insulating wall 39 between the two reservoirs. The respective temperatures of the water in the two reservoirs may be followed by observing thermometers 41, 41¹ and these respective temperatures may be regulated by changing the rate of feed or the temperature of the hot water fed to the machine or by manipulating the rate of discharge through valve 40.

Doors 42, 42¹ are provided for gaining access to the reservoir so that the various screens and refuse baskets may be removed and cleaned. Spraying tubes 24, 24¹, 29, 29¹ and 32, 32¹ are fastened to the casing of the machine by wing nuts 43 and may be detached for cleaning by loosening these nuts.

Turning now to the modification shown in 35 Figs. 6 to 9 inclusive, there is shown a ma-

chine differing mainly from the one already described in the arrangement of the conveying mechanism for the dishes. The dish baskets, in this embodiment of the invention, move through a circular compartment, instead of through straight washing and drying compartments, and are delivered back to their starting point. The conveyor for the dishes consists of a revoluble table 100 suitably supported by ball bearings on column 101 and by rollers 101^a. The table is divided by members 102 into compartments capable of receiving curved baskets 103. Dishes are loaded onto the table at station A, move through washing compartment B, then through drying compartment C and return to station A, washed and dried. The arrangement of wash water reservoirs and sprays is similar to that in the machine already described. Heat for drying the dishes is supplied here also as in the straight line type of machine by hot water heater 33. Draft for drawing hot air from the heater over the dishes is supplied by circular flue 34¹ fitted with baffles 37 and connected to chimney 35.

Movement of the rotating table is obtained in this type of machine simply by inclining the wash water heads or sprayers so that the water strikes the dishes forcibly on one side. The slow movement of the table 30 obtained insures thorough washing and drying and eliminates the necessity for a motor drive. In order that the slow movement of the table may be further assured, a brake may be provided actuated by a governor connected through the system of gears 104 to the rotating table. The gears 104 may, of course, be just as advantageously connected to a speed-regulating clock work mechanism, or to the shaft of a fan arranged to exhaust the air and vapors from flue 34¹.

In this embodiment of the invention a somewhat different arrangement for removing the screens from the wash-water reservoirs is shown. The screens 105 are disposed here radially and are held in position in the man-holes by doors 106 maintained closed by the screws 107. When it is necessary to clean the screens, screws 107 are loosened and doors 106 are swung on their pivots 108 out of the way. The screens may then be removed.

The system of moving the dishes by means of the washing jets, described in connection with this modification, may be applied as well to the straight line type of machine. It is only necessary in using this system of propulsion with the straight line machine to push the dish carriages into the washing compartments. The action of the washing jets then effects their continued motion through these compartments into the drying compartment.

I claim:

1. A machine of the class described comprising in combination a washing compartment, a rinsing head positioned in said wash-

- ing compartment and adapted to direct a jet of water on articles to be cleaned, a drying compartment communicating with the washing compartment, means for conveying articles to be cleaned first into the washing and then into the drying compartment, a water heater positioned under the drying compartment and in communication therewith so as to discharge heated air into the latter, a flue mounted over the washing compartment, a chimney connected to said flue and positioned to draw the heated air from the water-heater through the drying compartment into the washing compartment in the direction opposite to that of the movement of the articles being cleaned and finally into the flue, and a feed conduit extending from the water-heater to the rinsing head in the washing compartment.
2. A machine of the class described comprising in combination a washing compartment, a rinsing head positioned in said washing compartment and adapted to direct a jet of water on articles to be cleaned, a drying compartment communicating with the washing compartment, means for conveying articles to be cleaned first into the washing and then into the drying compartment, a water heater positioned under the drying compartment and in communication therewith so as to deliver heated air to the latter, and means connected to the washing compartment and operative to draw the heated air from the water heater through the drying compartment into the washing compartment in a direction opposite to that of the articles being cleaned, and a feed conduit extending from the water heater to the rinsing head in the washing compartment.
- 40 In testimony whereof I hereunto affix my signature.

JULES LOUIS BRETON.
